UNITED STATES PATENT OFFICE.

GEORGE C. WILLIAMS AND EDWARD A. WILLIAMS, OF BROOKLYN,
NEW YORK.

BOWED NURSERY WINDOW-GUARD.

SPECIFICATION forming part of Letters Patent No. 708,442, dated September 2, 1902.

Application filed April 16, 1902. Serial No. 103,238. (No model.)

To all whom it may concern:

Be it known that we, GEORGE C. WILLIAMS and EDWARD A. WILLIAMS, citizens of the United States of America, and residents of the 5 borough of Brooklyn, New York city, State of New York, have invented certain new and useful Improvements in Bowed Nursery Window-Guards, of which the following is a specification.

10 Our invention relates to bowed nursery window-guards of wire-netting, such as are detachably connected to the window-casing; and it consists of improved construction of such guards extensibly for adapting them to 15 windows of different widths, as hereinafter described, reference being made to the accompanying drawings, in which—

Figure 1 is an elevation of our improved extensible guard applied to a window and as 20 seen from the outside. Fig. 2 is a plan view of the top bar of the frame. Fig. 3 is a front elevation of part of the top bar of the frame enlarged for greater clearness. Fig. 4 is a transverse section of the top bar on the line 25 4 4 of Fig. 2, also enlarged. Fig. 5 is a plan view of part of the lower frame-bar. Fig. 6 is a front elevation of the part of the lower frame-bar shown in Fig. 5.

Two horizontal bow-shaped frame-bars A 30 and B are used, which, together with the vertical connecting and supporting rods a, mainly constitute the frame on which the inclosing protective web of wire-netting b is applied. The upper frame-bar comprises a middle main 35 part c, two end sections d, and two coupling-pieces e, all being of channel form in cross-section, the channel being in the under side, as shown in Fig. 4. The middle part c is a straight bar, the coupling parts e are of elbow 40 form, and the end sections d are also straight bars, preferably; but they may be curved horizontally, if desired. The bar c laps at each end in the channels of coupling-sections e at one end and are riveted fast at g. The 45 bars d lap in the channels of the other ends of couplings e and are pivoted at h, so as to have slight lateral play. At their other ends said bars d have an eye by which they are connected to the supporting-rods a, respectively, said rods being connected to the window-frame i by eye-screws, as at j, and by

wood-screws, as at k, or any other approved means.

In the channels of the respective parts of the upper bar A a strong wire l is placed and secured at intervals by hooks m, riveted in the middle sections of the channel parts, said wire being suitably bent in the angles of the elbow-sections e to serve as stiffeners to the bow-angles of the frame and prevent too free 60 flexure at said angles, where only sufficient flexure is required for adjustment of the bow ends of the frame within about such limits as indicated in Fig. 2 of the drawings. The terminals n of the side walls of the channels 65 of parts e are relied on to positively limit the play of parts d against excessive movement. The upper edge of the netting b is interwoven with other hooks or rings o, carried on wire l, for connection with the upper frame-bar. 7c

The lower bow-shaped frame-bar B comprises a middle straight rod p and two lateral arms q of like character, which are suitably flattened and riveted together at the angles of the bow, as shown at s, with slight allowance 75 for articulation in adjusting the extremities of the frame to the different windows of varying widths. The lower edge of the web b is woven onto these rods in the usual manner.

Such bowed guards enable a window-cleaner 80 to reach the outside of the window conveniently without removing them.

What we claim as our invention is—

1. In an adjustable wire-netting bowed nursery window-guard, the combination with the 85 upper bow-frame comprising the middle inverted channel-bar, inverted elbow channel parts lapped and riveted at one end to the ends of the middle bar respectively, and inverted channel-end bars pivoted in the other 90 ends of the elbow parts; of the supporting-rods adapted to be attached to the window-frame, said end bars and supporting-rods connected by said rods being inserted in eyes of the end bars. 95

2. In an adjustable wire-netting bowed nursery window-guard, the combination with the upper bow frame-bar comprising the middle inverted channel-bar, inverted elbow channel parts lapped and riveted at one end to the 100 ends of the middle bar respectively, and inverted channel end bars pivoted in the other

- ends of the elbow parts; of the supporting rods adapted to be attached to the window-frame and connected to the ends of said channel end bars, the continuous wire placed in the channels of the several parts of the frame-bar, and secured to the respective parts at intervals along the middle of the channels, and the wire-netting interwoven along the upper edge with said wire.
- 10 3. In an adjustable wire-netting bowed nursery window-guard, the combination with the upper bow frame-bar comprising the middle inverted channel-bar, inverted elbow channel parts lapped and riveted at one end to the ends of the middle bar respectively, and inverted channel end bars pivoted in the other ends of the elbow parts, of the supporting rods adapted to be attached to the window-

frame, and connected to the ends of said channel end bars, the continuous wire placed in the channels of the several parts of the frame-bar and secured to the respective parts, at intervals along the middle of the channels, the wire-netting interwoven along the upper edge with said wire, and the lower frame-bar 25 jointed at the angles of the guard and secured to the supporting rods, and having the lower edge of the wire-netting interwoven with it.

Signed at New York this 11th day of April, 1902.

GEO. C. WILLIAMS.
